UNITED STATES PATENT OFFICE

RAYMOND G. F. LOEWY, OF JACKSON HEIGHTS, NEW YORK

DESIGN FOR A RADIATOR FOR AN AUTOMOBILE

Application filed July 9, 1928. Serial No. 27,423. Term of patent 7 years.

To all whom it may concern:

Be it known that I, RAYMOND G. F. LOEWY, a citizen of the Republic of France, residing at Jackson Heights, Long Island, county of Queens, and State of New York, have invented a new, original, and ornamental Design for a Radiator for an Automobile, of which the following is a specification, reference being had to the accompanying drawing, forming part thereof.

Figure 1 is a front view, and
Figure 2 is a side view showing my new design.

I claim:

The ornamental design for a radiator for an automobile as shown.

In testimony whereof I have affixed my signature to this specification.

RAYMOND G. F. LOEWY.
